Patented Oct. 20, 1914.

UNITED STATES PATENT OFFICE.

STEPHEN T. STUVER, OF TACOMA, WASHINGTON.

SHREDDING-MACHINE.

1,114,411.

Specification of Letters Patent. Patented Oct. 20, 1914.

Application filed February 27, 1912. Serial No. 680,254.

To all whom it may concern:

Be it known that I, STEPHEN T. STUVER, a citizen of the United States, and a resident of Tacoma, in the county of Pierce and State of Washington, have invented a new and Improved Shredding-Machine, of which the following is a full, clear, and exact description.

My invention relates generally to vegetable shredders and more particularly to a new and improved device involving few parts of simple construction, the rotatable element therein being removable whereby a similar element, but one providing for a different degree of shredding, may be inserted.

The principal object of my invention is to provide a vegetable shredder comprising a suitable casing with a rotatable shredding element mounted therein, this shredding element taking a plurality of forms whereby different degrees of shredding may be obtained.

Other objects and advantages of the invention will appear as the description thereof proceeds, the new and useful features being pointed out in the appended claims.

Reference is to be had to the accompanying drawings forming part of this specification, in which similar characters of reference denote corresponding parts in all the views, and in which—

Figure 1 is a perspective view of the shredder in operative position; Fig. 2 is a vertical sectional view thereof; Fig. 3 is a vertical sectional view at right angles to Fig. 2; Fig. 4 is a perspective view of a modified form of shredding element.

As shown in the drawings, the device comprises any suitable standard 1 having a plurality of lugs 2, 3, extending transversely thereof and adjacent one end, the lug 3 being provided with a transversely movable bolt 4 whereby the device may be positioned adjacent the edge portion of any support 5.

The upper end 6 of the standard 1 is preferably circular in formation and is provided with a transversely extending opening 7 through which the threaded shaft 8 extends, there being a handle 9 having a screw-threaded opening 10 adjacent one end thereof in engagement with the shaft 8, whereby turning of the handle will turn the shaft.

Secured to the upper end 6 of the standard 1 is the casing 11, preferably held in position by means of bolts and nuts 12, the

upper portion of this casing being provided with an opening, there being a hopper 13 adjacent thereto adapted to receive vegetables or other substances. This casing member 11 is preferably frusto-conical in construction, one end thereof being closed by the member 14 which lies closely adjacent the upper end 6 of the standard 1. The other end of the casing member 11 is open, this open end being the end of larger diameter whereby the revoluble shredding element 15 or 15^a may be conveniently placed in position.

The inner end of the threaded shaft 8 is provided with a frusto-conical supporting member 16 having a number of lugs 17 on the outer side and extending normally therefrom, these lugs being adapted to be received in the openings 18 positioned adjacent the smaller end of the shredding element 15 or 15^a.

The shredding element 15 is preferably of frusto-conical formation and is provided with a number of outwardly bent blades 19 which may be of any desirable construction, the other shredding element 15^a being provided with continuously extending blades 20, the blades in each form extending beyond the outer surface of the element and within the open space between the inside of the casing member 11 and the revoluble element 15 or 15^a.

The hopper 13 is designed to receive a suitable number of vegetables or other substances which are to be shredded, turning of the handle 9 rotating the shredding elements and bringing the outer edges of the blades into engagement with the vegetables whereby suitable portions are removed from them which pass through the openings in the elements adjacent the blades, the shredded material leaving the open end of the elements and being received in any suitable receptacle. If so desired, the hopper 13 may be provided with a movable element 21 in the nature of a cover adapted to be pressed down against the vegetables or other substances and bring them into firm engagement with the blades of the rotatable shredding elements.

The shredding elements shown differ from each other only in the particular form of blades provided thereon, it being obvious that the construction and operation of the device remain the same whatever the form of blade; the blades are easily changed by

removing the handle 9 and withdrawing the circular supporting member 16, after which the shredding element thereon may be taken off and the other form placed in position.

5 Having thus described my invention, I claim as new, and desire to secure by Letters Patent:—

1. In a shredding machine, the combination of a conical casing having its smaller 10 end closed, and a shredding element mounted in the casing, said element comprising a disk-like member having a frusto-conical flange and a centrally arranged shaft projecting therefrom, said flange being provided 15 with external pins, and an open ended frusto-conical tubular body having peripheral blades and provided with L-shaped openings at its smaller end, the horizontal portions of the openings being adjacent the 20 smaller end of the body and the longitudinal portions extending in the direction of the opposite larger end of said body, the smaller end of the body fitting upon the said flange with the pins thereof engaging its 25 slots and its end closely adjacent the closed end of the casing.

2. In a shredding machine, the combina-

tion of a support, a frusto-conical casing having its smaller end closed and secured to the support, the closed end of the casing and support having registering openings, a disk-like member having a frusto-conical flange and a central shaft mounted in the openings of the support and casing, the said flange being provided with pins on its periphery, and a frusto conical tubular body open at both ends and provided with peripheral blades and in its smaller end with L-shaped openings, the said smaller end of the body being closely adjacent said closed end of the casing and fitting on the said flange with the pins of the flange projecting into the openings of the body, whereby the body can be readily attached to or removed from the disk-like member and when attached and the parts are in position the body is securely held on the said member.

In testimony whereof I have signed my name to this specification in the presence of two subscribing witnesses.

STEPHEN T. STUVER.
